United States Patent Office.

IMPROVEMENT IN RETORTS FOR THE MANUFACTURE OF ILLUMINATING GAS.

ADOLPH MILLOCHAU, OF NEW YORK, N. Y., ASSIGNOR TO AMERICAN IMPROVED GAS RETORT COMPANY.

Letters Patent No. 60,537, dated December 18, 1866.

The Schedule referred to in these Letters Patent and making part of the same.

TO ALL WHOM IT MAY CONCERN:

Be it known that I, ADOLPH MILLOCHAU, of the city and State of New York, have invented and made a certain new and useful Improvement in Retorts for the Manufacture of Illuminating Gas; and I do hereby declare the following to be a full, clear, and exact description of the said invention, reference being had to the annexed drawing, making part of this specification, wherein—

Figure 1 is a longitudinal section of my improved retort; and

Figure 2 is a cross-section of said retort at the line *xx*.

Similar marks of reference denote the same parts.

Retorts have heretofore been made, in which the products of distillation have been subjected to a re-heating previously to their passing to the hydraulic main. This re-heating has been effected in a separate retort, and has not removed the difficulty experienced from the formation of tar by the dense carbonaceous matters evolved by the coal under the action of the intense heat to which the coal is subjected when first introduced into the retort.

The nature of my said invention consists in a platform or false bottom, introduced within the retort, for sustaining the coal, and allowing a space below said platform for the products of distillation to be more perfectly combined by the great heat to which they are exposed in passing through said space, and going off by a casing at the end of the retort to the hydraulic main. By this construction a much more perfect gas is produced, because the carbonaceous matters are more intimately combined than heretofore, and the production of tar and similar matter is lessened.

In the drawing, *a* represents a retort of any desired size or shape; *b* is the flanged end of the retort; *c* is the platform, sustained upon short studs or legs *ii*, and having an end piece *d*, with a cap-plate *e*; *f* is a casing, with a flange *g* bolted to the flange *b*, and the end piece *d* is between the flanges *f* and *g*, and is packed gas-tight at this point. *h* is the cap-plate or cover to the casing *f*, secured in place by a cross-bar, and rendered gas-tight by a luting of clay, as usual. *l* is the pipe rising to the hydraulic main.

The cover *h* is to be removed, and the cap-plate *e* turned down; the coal is then introduced upon the false bottom or platform *c*, and the cap-plate *e* turned up or closed, and the cover *h* replaced. The carbonaceous vapors evolved from the coal by the heat pass down through the pipes *k* of the platform *c*, and travel along between said platform and the highly heated bottom of the retort; the result of which is that the gaseous matters are more perfectly combined to produce an illuminating gas, and any uncombined or tarry matters that may remain from one charge are vaporized, and combine with the gases passing off towards the end of the operation, or with those evolved from the next charge, thus lessening the production of tar and increasing the illuminating qualities of the gas.

What I claim, and desire to secure by Letters Patent, is—

The platform or false bottom *c*, openings or pipes *k*, and cap-plate *e*, in combination with the retort *a*, substantially as and for the purposes set forth.

In witness whereof I have hereunto set my signature this thirty-first day of October, A. D. 1866.

A. MILLOCHAU.
